Inventor,
W. H. Glasgow

UNITED STATES PATENT OFFICE.

WILLIAM H. GLASSGOW, OF NEW YORK, N. Y.

BARREL-PACKER.

Specification of Letters Patent No. 23,243, dated March 15, 1859.

To all whom it may concern:

Be it known that I, W. H. GLASSGOW, of the city, county, and State of New York, have invented a new and useful Device for 5 Packing Barrels; and I do hereby declare that the following is a full, clear, and exact description of the same, reference being had to the annexed drawings, making a part of this specification, in which—

10 Figure 1, is a vertical section of my invention taken in the line x, x , Fig. 2. Fig. 2, a plan or top view of ditto.

Similar letters of reference indicate corresponding parts in the two figures.

15 This invention relates to a new and useful machine for packing various substances in barrels, such substances as may be packed sufficiently by striking or jarring the barrels as cement, plaster, sugar, and the like.

20 The invention consists in giving the barrel while being filled a rotary motion and subjecting it to a lateral and vertical jarring movement, either or both, and simultaneously with its rotating movement, to accomplish 25 the desired end.

To enable those skilled in the art to fully understand and construct my invention I will proceed to describe it.

20 A, represents a platform or flooring underneath which a power shaft B, is operated by gearing a, b . On the inner end of the shaft B, a bevel wheel c , is placed, said wheel gearing into a wheel d , which is attached to the under side of a cam C, said cam being fitted 35 loosely on a stationary hollow axis D, which is placed in a beam e , below the flooring. The upper surface of the cam C, is about “flush” with the upper surface of the flooring A. This cam is constructed by having 40 projections f , of saw-tooth form at the edge of a circular disk or plate as shown clearly in Fig. 2. On the upper surface of the cam C, and concentrically with it, an annular ledge g , is formed of such size that the lower 45 chimes of the barrels to be packed may fit over it. Within said ledge a circular plate E, is placed, said plate being attached to the upper end of a spindle F, which passes loosely through the axis D, of the cam C,

and has a horizontal arm h , attached to its 50 lower end, said arm resting on a stationary annular cam G, which is attached to the lower ends of pendants i , secured to beam e . The cam G, is merely a wing j , having inclined projections k , attached to its upper 55 surface as shown clearly in Fig. 1. To the underside of the plate E, two pendant rods l, l , are attached, said rods fitting loosely in the cam C.

H, is a hammer which is secured to the 60 upper end of a rod I, said rod being fitted loosely on an axis m , below the flooring A, and having a spring n , bearing on it below its axis, as shown clearly in Fig. 1. The spring n , keeps the rod I, against the edge 65 of the cam C.

The operation is as follows:—The barrel J, to be packed is placed on the cam C, and the lower chime over the ledge g , and the substance may be allowed to run into the barrel while the latter is being acted upon. The shaft B, is rotated by any proper means and the cam C, as it rotates communicates motion to the barrel J, the barrel being retained on the cam by its weight. As the cam 70 C, rotates the plate E, is also rotated in consequence of the pins l, l , and said plate rises and falls by means of the arm h , at the lower end of the spindle F, resting on the cam G, and the barrel J, is thereby subjected 75 to a vertical jarring movement, the pins l , being sufficiently long to permit such movement without disconnecting the plate E, from cam C, and the cam C, as it and the barrel J, rotate forces out the hammer rod 80 85 I, so that the hammer will by means of the spring n , be brought against the side of the barrel as the projections f , pass the rod I. The barrel therefore will be rotated and jarred both vertically and laterally while being filled and its contents properly placed 85 90 within it.

I would remark that the up and down movement of plate E, might in certain cases be dispensed with, the hammer H, performing the work alone. The hammer H, also might be dispensed with in certain cases, and the vertical jarring movement alone 95

used, but the joint operation of all the parts would be preferable in a majority of cases.

Having thus described my invention what I claim as new and desire to secure by Letters Patent, is,

- 5 1. The rotary cam C, with barrel J, attached in connection with the vibrating hammer H, arranged to operate as described.
2. The plate E, having a rotary and a

vertical reciprocating movement for the purpose specified, and

3. The cam C, plate E, and hammer H, arranged for joint operation substantially as and for the purpose set forth.

WM. H. GLASSGOW.
